UNITED STATES PATENT OFFICE.

JOHN P. GERAGHTY, OF JERSEY CITY, NEW JERSEY.

SAFETY DEVICE FOR INTERNAL-COMBUSTION ENGINES.

Application filed February 12, 1925. Serial No. 8,799.

This invention relates to improvements in safety devices for internal combustion engines and has for an object to provide a construction wherein the engine may be started or stopped either manually or electrically.

Another object of the invention is to provide a device for internal combustion engines wherein means are provided which may be either electrically or manually operated and, when operated, cause the starter to be disconnected from its source of current as soon as the engine begins to function.

A still further object of the invention is to provide a safety device for internal combustion engines wherein a starting button, lever or other structure may be held in functioning position for a long time, and yet the starter will be thrown out of operation immediately upon the functioning of the engine.

In the accompanying drawings—

Figure 1 is an elevation of the principal part of the mechanism embodying the invention;

Fig. 2 is a sectional view through Fig. 1 on the line 2—2;

Fig. 3 is a fragmentary view, partly in section, showing how the ignition circuit is broken;

Fig. 4 is a view similar to Fig. 3 but showing the circuit closed;

Fig. 5 is a view similar to Fig. 1, but on a reduced scale and looking at the structure from the opposite side;

Fig. 6 is a view similar to Fig. 5, but showing an electrically-operated structure instead of a mechanically-actuated structure;

Fig. 7 is a schematic view showing the various contacts and associated parts of the apparatus, which control the current to the various parts of the engine;

Fig. 8 is a vertical sectional view through Fig. 1 approximately on the line 8—8;

Fig. 9 is a face view of the switch plate shown in Fig. 8;

Fig. 10 is an enlarged perspective view of the resetting arm embodying certain features of the invention.

In constructing the device embodying the invention, means have been provided for either manually or electrically closing the switches of the starter, ignition and the generator of an internal combustion engine and later automatically opening the circuit of the starter while leaving the circuits of the

generator and ignition closed. Means have also been provided for closing the circuit of the starter except at one point when the engine is stopped and opening the circuit from the starter to the battery.

In constructing a device as outlined, a suitable frame or housing is provided, which may be of any desirable material, but which is preferably made in two parts, as shown in Fig. 8, so that the mechanism enclosed thereby may be readily applied or removed. As indicated particularly in Fig. 8, the casing 1 is provided with a hollow boss 2 for accommodating the shaft 3, and other suitable hollow bosses for accommodating certain other shafts or supporting members. A resetting arm 4 is rigidly secured to shaft 3 in any desired manner, such arm having an offset 5 adapted to engage the projection 6 extending from the flange 7 formed on a sleeve 8. The sleeve 8 snugly fits into the switch disk 9 and is clamped into position by a suitable nut 10, whereby the parts rotate together. A spring 11 is provided and so positioned that one end is extended into the casing 1, while the opposite end extends into the disk 9. This spring normally tends to move the disk 9 clockwise from the position in Figures 3 and 7 to the position shown in Fig. 4 and will do so when catch 28 is released. Means have been provided as hereinafter described, which will move the disk to the position shown in Figs. 3 and 7, whereby the spring 11 will be brought under tension and whenever released will cause the disk 9 to again assume the position shown in Fig. 4. The disk 9 is provided with a pair of contact plates 12 and 13. The contact plate 12 coacts with contact posts 14 and 15, while the contact plate 13 coacts with the contact posts 16 and 17. Each of the contact posts 14 and 15 is provided with a contact member 18 and caused to frictionally engage the plate 12 by suitable springs 19 carried in a socket formed in the various holding members 20, which are clamped in position by suitable nuts 21. The posts 16 and 17 are each provided with a reciprocating contact member 22 and caused to function properly by reason of the spring 23 positioned in a socket in the supporting member 24, which supporting member 24 is clamped firmly in place by a suitable nut 25. The contact member 22 of the post 17 is provided with a pair of notches 26, which are adapted

to receive a wire or other member, which will be positioned therein and wound around the contact 22 when the contact is pulled away from the plate 13. This will lock or firmly maintain the contact 22 out of engagement with the plate 13, and thereby permanently hold the circuit of the starter 27 open. This is desirable when the starter is out of order or when it is desired to repair certain parts.

In order to hold the disk 9 in the position shown in Fig. 7, after arm 4 has been moved away from projections 6, a resilient catch 28 is provided, which has a tendency to move in such a direction that the turned-over end will fit into the notch 29. One or more magnets 30 are provided, and when energized act to pull the catch 28 away from the disk 9, whereby spring 11 will begin to function and return the parts to the position shown in Fig. 4, whereby the circuit of the starter 27 is opened.

In operating the shaft 3, electrically-operated means may be used, or, if preferred, manually-actuated means may be employed. As shown in Fig. 5, the shaft 3 is rigidly secured to an arm 31, which in turn is pivotally connected, as at 32, to the link 33 at the point 34, and pivotally connected to one arm of a bell crank lever 35, the opposite end being pivotally connected, as at 36, to the thrust rod. The thrust rod 37 may be moved back and forth by hand, or may be connected to locking means which when operated will cause the desired back-and-forth movement to give the shaft 3 the desired rocking action.

In Fig. 6, an electrically-operated structure is presented wherein a core 38 is substituted for the thrust rod 37 and associated with a solenoid 39. A second core 40 is also pivotally connected to the bell crank lever 35, in the opposite direction to the core 38. The winding of the solenoid 39 is connected through a suitable conductor to a source of current 42, and to a circuit-closing structure 43, which may be a push-button, key, or other suitable closing structure. When the circuit closer 43 is caused to function for closing the circuit of the solenoid 39, the core 38 will be pulled and the shaft 3 will be rocked in one direction. When the circuit-closing structure 44 is closed, the solenoid 41 will be energized and the core 40 pulled, moving the parts in the opposite direction or back to the position shown in Fig. 6. The circuit closer 44 may be a push-button, key, or other device, as desired. From this it will be seen that the shaft 3 is rocked in both directions by electrically-operated means, and the various parts shown in Figs. 7 and 8 caused to function as heretofore described.

When the engine is to be started and the parts are in the position shown in Figure 3,

the thrust rod 37 is moved inwardly and the shaft 3 rocked a certain distance. In case the structure shown in Fig. 6 is to be used, the circuit closer 43 is closed temporarily and the shaft 3 will be rocked in a similar manner. The rocking of the shaft 3 will cause the arm 4 to move away from rod 47 whereupon spring 48 will function to cause contact 46 to move into engagement with contact 45. Immediately that the parts are moved to the position shown in Fig. 7, the various circuits are closed through the plates 12 and 13, and also through the ignition switch 45. This switch is formed in two parts, preferably, and connected by a connecting contact 46 secured to the rod 47, which rod and connecting contact 46 are moved to a closed position, as shown in Fig. 4, by a spring 48. However, when the parts are moved to the position shown in Fig. 7, as above set forth, the circuits are all closed and immediately current will pass from the storage battery 49 to the wire 50 and from thence to the various spark plugs and to the starter 27. As soon as the starter 27 has begun to function, the generator 51 will begin to impress current on the line, and as soon as this takes place, the magnets 30 will begin to function. The device 51' functions to allow current to pass from the generator to line 50 but acts to prevent current flowing in the opposite direction, thus permitting the generator to charge the battery but preventing waste of current from the battery to the generator when the generator is stationary.

In tracing the circuit for the ignition at the starting of the engine, current will pass from the storage battery 49 to wire 50, through switch 45 and contact member 46, wire 53, through the primary coil 54, and thence to the ground. This will induce current in the secondary of the coil whereupon the distributor 55 will be provided with high tension current. At the same time that current flows through the ignition circuit, as above described, current will pass from wire 52 to the contact post 16, plate 13, contact post 17, wire 56, starter 27 and from thence to the ground, whereupon the starter will begin to function for turning over the engine. As soon as the engine turns over, the generator 51 will begin to function and current will pass from thence to the contact post 15, plate 12, contact post 14, wire 56, electromagnets 30 and from thence to the ground. As soon as this takes place, the catch 28 will be pulled away from the disk 9 and the tension of the spring 11 will then rotate the disk clockwise as arrow 9' indicates for a distance or until the parts assume the position shown in Fig. 4. This will cause the plates 12 and 13, respectively, to move away from posts 14 and 17, which action deprives the magnets 30 and also the starter 27 of current.

but leaves the ignition circuit closed and also the circuit of the generator to the ignition and to the battery 49 closed.

When it is desired to stop the engine, the 5 shaft 3 is rocked in the opposite direction by either the solenoid 41 or the rod 37. This reverse rocking of the shaft will cause the arm 4 to move to the position shown in Fig. 3, and which action will cause the arm 4 to 10 strike the projection 6 and rotate the disk 9 until the switch 45 is opened and until catch 28 again moves into the notch 29, spring 11 being also brought under tension. When 15 this occurs, the contact posts 14 and 15 will again rest on the plate 12, while the contact posts 16 and 17 will rest on the plate 13, but neither the generator nor the starter can function because the circuit of the starter is 20 opened by the opening of the switch 45 and the action of the generator is stopped by reason of the stopping of the engine as the spark plugs thereof will not function.

To again start the engine, it is only necessary to close the switch 45 by rocking the 25 shaft 3 as heretofore described, and the various actions above described will take place. It will thus be seen that a key, push button, or similar circuit closer, may be used for causing an electrical starting or stopping of

the engine when the construction in Fig. 6 30 is utilized. When the construction shown in Fig. 5 is utilized, the back-and-forth movement of the rod 37 will cause the proper action of the various parts.

What I claim is:

A switch including a rock shaft, an arm extending from the rock shaft, a pair of contacts forming part of a circuit, a rod formed with a connecting contact for connecting the first mentioned contacts, said arm acting to 40 move said rod for moving the connecting contact from out of engagement with the other contacts, a spring for moving said arm and said rod in a direction opposite to the movement caused by said arm for causing 45 said contacts to engage, a switch disk moved in one direction by said arm, a pair of contact plates carried by said disk and acting as part of a second circuit, said plates being positioned to close said second circuit when 50 moved by said arm, a spring for moving said disk and plates in a direction opposite to the movement of said arm whereby said second circuit is opened, and a catch co-acting with said disk for normally locking the 55 same against movement.

JOHN P. GERAGHTY.
